UNITED STATES PATENT OFFICE.

RICHARD MARTIN BECKER, OF NICOLLET, MINNESOTA.

CHURN GUARD.

Application filed December 15, 1928. Serial No. 326,267.

This invention relates to guards for machinery and pertains particularly to a guard designed for use upon a rotary churn.

The primary object of the present invention is to provide a guard which may be shifted to a position in front of the cylinder of a rotary churn to prevent accidental contact therewith by an attendant and which, when the churn has been stopped, may be swung to a predetermined lowered position which will permit the attendant to reach the churn without difficulty.

Another object of the invention is to provide a swinging guard of the above described character having an improved sliding swinging connection with a fixed supporting bracket which may be rigidly secured to a suitable fixed portion of the machine in association with which the guard is to be used.

Other objects of the invention are to provide a guard which is of simple construction, designed to be easily mounted in position, strong and durable and comparatively inexpensive to manufacture.

The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a plan view of one end of a rotary cylinder churn showing the application thereto of a device embodying the present invention;

Figure 2 is a view in side elevation of one of the two guard bar supporting members mounted in position at one end of the churn;

Figure 3 is a sectional view taken longitudinally of the inner end of a supporting arm of the guard showing the detailed structure thereof;

Figure 4 is a sectional view taken upon the line 4—4 of Figure 3.

Referring to the drawing in detail wherein like numerals of reference indicate corresponding parts throughout the several views, there is shown a revolving churn, the body of which is in the form of a drum, as indicated by the numeral 1 of the type in asso-

ciation with which the present guard device is designed to be used.

As shown, this churn is mounted between supporting brackets 2 upon trunnions 3, which support it to revolve about its longitudinal axis, the top of each bracket being formed to provide the lower half of a bearing and laterally flanged as indicated at 4 to receive the corresponding flange portions 5 of a bearing cap 6. The flange portions 4 and 5 are held together in the usual manner as by the bolt 7.

These rotating drums are usually rotated by the connection of a suitable driving mechanism with a gear such as that indicated by the numeral 8 which is mounted at one end of the drum upon a trunnion.

In churning of this character at present in use the guards employed are not shiftable and difficulty is therefore experienced by the attendant of the churn in removing butter therefrom.

The present invention comprises a guard which is adapted to be lowered and consists of a pair of bifurcated brackets 9, the end portions 10 of the furcations each being arranged in spaced relation in the manner shown and designed to receive therebetween a pair of the flanges 4 and 5 of the bearing, the bolt 7 which holds these flanges together passing through the ends of the furcations to maintain the bracket in forwardly extending substantially horizontal position.

Formed longitudinally of each bracket is a slot 11 and at the free or forward end thereof the top is provided with a number of notches 12.

Associated with each of the brackets 9 is a guard bar supporting arm 13. Each of the arms 13 is longitudinally divided at its inner end forming the spaced parallel members 14 each of which carries an upwardly projecting semi-circular body 15.

Each of the arms 13 receives between its members 14 one of the brackets 9 and the members of each arm are connected at their rear ends by a bolt or pin 16 which passes through the slot 11 of the adjacent bracket and carries a roller body 17 which acts as a bearing in the slot.

The semi-circular bodies 15 of each arm have formed therethrough a series of aligned apertures 18 for the reception of a bolt or pin 19 which carries a spacing roller 20. The pin and roller structure of each arm is normally positioned above the adjacent

bracket so that when the arm is allowed to swing down the roller 20 will come to rest upon the top edge of the adjacent bracket. The arms 13, the outer ends of which are connected by the guard bar 20^a which extends longitudinally of the face of the churn drum, when in this downwardly extending position support the guard bar across the lower part of the churn machine, thus permitting an attendant to have free access to the interior thereof.

The members 14 of each arm adjacent their inner ends are provided with a series of transversely alined apertures 21 and extending through one pair of alined apertures between the members is a bolt 22 which carries a sleeve 23.

When the guard bar is to be placed in guard position it is first raised until the pin or bolt 22 of each of the arms is swung upwardly past the outer end of the adjacent bracket 9 after which the guard bar and arms are shifted inwardly, the bolts 16 sliding in their respective slots 11 until the pins 25 and bushing 22 and 23 are in a position to be lowered into one of the recesses 12 of the underlying bracket. The guard bar is then dropped until this positioning of the bushings 23 in the recess of the adjacent 30 brackets takes place following which the bar may be released and will remain in raised position as will be understood.

While the foregoing description refers particularly to bifurcated brackets it will, 35 of course, be understood that I do not wish to be limited to the detailed structure of the bracket as shown, for it is obvious that suitable brackets may be constructed of solid plate as well as from a member having a 40 pair of independent arms as shown.

From the foregoing description it will be readily understood that the guard bar embodying this invention may be easily and quickly lowered from upright position or raised thereto as desired with a minimum of effort.

Suitable adjustments may also be made through the provision of the plurality of apertures 18 and 21 so that the distance 50 downwardly to which the guard may be swung may be regulated and the space between the guard bar and the churn drum increased or decreased as desired.

Having thus described my invention, what 55 I claim is:—

1. A shiftable guard support, comprising a rigidly mounted bracket, an arm, means to provide a sliding pivotal connection between one end of said arm and said bracket, 60 and means for coupling the arm with the bracket to maintain the same in substantially parallel relation thereto.

2. A shiftable guard support, comprising a rigidly mounted bracket, an arm, means 65 to provide a sliding pivotal connection be-

tween one end of said arm and said bracket, means for coupling the arm with the bracket to maintain the same in substantially parallel relation thereto, and means carried by the arm for engagement with the bracket 70 to limit the movement of the arm in one direction.

3. A guard structure of the character described, comprising a pair of bracket members designed to be rigidly substantially 75 horizontally supported, an arm member associated with each of said brackets, a sliding pivotal connection between one end of each arm and its associated bracket, a guard arm connecting the other ends of the arms, and 80 means for pivotally connecting each arm intermediate its ends with its associate bracket to maintain the arms and guard bars in substantially the same plane as the brackets.

4. A guard structure of the character described, comprising a pair of bracket members designed to be rigidly substantially 90 horizontally supported, an arm member associated with each of said brackets, a sliding pivotal connection between one end of each arm and its associate bracket, a guard bar connecting the other ends of the arms, means for pivotally connecting each arm 95 intermediate its ends with its associate bracket to maintain the arms and guard bars in substantially the same plane as the brackets, and means for limiting the downward swinging movement of the arms on their brackets.

5. A guard for a machine of the character described, comprising a pair of bracket members designed to be rigidly mounted in substantially horizontal position at opposite sides of the machine, each of said brackets 105 having a longitudinally extending slot, an arm member associated with each bracket, a coupling pin between each arm and its bracket and slidably engaging in the slot thereof, a guard bar connecting the other 110 ends of the bracket arms, and means for coupling the arms intermediate their ends with their respective brackets, when brought to a position substantially parallel therewith.

6. A guard for a machine of the character 115 described, comprising a pair of brackets each having a longitudinal slot and each designed to be mounted in substantially horizontal position at opposite sides of the machine, arm members each associated with a bracket and having sliding pivotal connection at one end in the slot thereof, a pin member carried by each arm designed to rest in a receiving recess formed in the top of the adjacent bracket, and a guard bar connecting 120 said arms at their outer ends.

7. A guard for a machine of the character 125 described, comprising a pair of brackets each having a longitudinal slot and each designed to be mounted in substantially hori- 130

zontal position at opposite sides of the machine, arm members each associated with a bracket and having sliding pivotal connection at one end in the slot thereof, a pin member carried by each arm designed to rest in a receiving recess formed in the top of the adjacent bracket, a guard bar connecting said arms at their outer ends, and a move-

ment limiting member carried by each of said arms above the inner end thereof for engagement with the adjacent bracket when the arm is swung downwardly.

In testimony whereof I hereunto affix my signature.

RICHARD MARTIN BECKER.
